HEINRICH ELSNER, OF DRESDEN, GERMANY

RIVETING MACHINE

Application filed April 16, 1929. Serial No. 355,611.

The present invention relates to a riveting machine adapted particularly for riveting or stitching fiber, board, leather or the like.

As it is generally desirable to employ a riveting machine capable of two operations, two different anvils are required one of which may be flat and the other angular. The flat anvil serves for riveting flat material while the angular anvil is used for working objects having walls and corners such as trunks, boxes, cartons and the like.

It is known to the prior art to arrange two different kinds of anvils interchangeably in the machine frame so that one of them had to be removed before the other could be put on. The work of unscrewing and securing anvils is quite bothersome, takes up much time, and, owing to the weight of the anvils, often requires special labor or auxiliary machinery. It is further known to combine flat and angular anvils into a unit representing a stationary table which is placed either into a level or saddle-shaped table.

The present invention provides a flat and an angular anvil rotatably secured to a vertical shaft fixed to the machine frame so that they can be turned into working position to suit requirements. Preferably, the anvils are interconnected so that the turning of one causes the rotation of the other. Both anvils can be held in any position by a locking device.

One embodiment of the invention is illustrated in the accompanying drawing, in which Figure 1 is a side view of the riveting machine with the rivet supply device removed; Fig. 2, a front view of same; and Fig. 3, a horizontal section on the line 3-3, Fig. 1.

Referring to the drawings, 1 is the machine frame with the driving pulley 2 and the treadle 3. From the drive the connecting rod 4 leads to the double-armed lever 5 carrying at its end the punch 6 which obtains the rivets 7 from the supply device 8. When the machine is actuated by the treadle 3, the punch 6 executes an up and down motion in order to effect riveting.

The machine frame 1 is provided with a vertical shaft 9 on which a flat anvil 10 and an angular anvil 11 are rotatably arranged.

12 is a locking device by means of which the anvils may be held in any desired position. The manner of riveting is indicated in the drawings by broken lines referring to the various positions of the work 13.

The anvils are brought in working position under the punch 6 to suit requirements, and their connection is preferably of a type to cause one anvil to cooperate in the rotation of the other.

I claim:—

A riveting machine with a flat anvil and an angular anvil rotatably arranged so that the turning of one causes the other to rotate characterized in that the two anvils are arranged on a special vertical shaft fixed to a vertical part of the machine frame.

In testimony whereof I have affixed my signature.

HEINRICH ELSNER.
